DESIGN FOR A COMBINED ULTRAVIOLET LAMP AND SHIELD

Norman A. Whittaker, Seattle, Wash.

Application May 7, 1947, Serial No. 138,860

Term of patent 14 years

(Cl. D48—20)

To all whom it may concern:

Be it known that Norman A. Whittaker, a citizen of the United States, residing at Seattle, King County, Washington, has invented a new, original, and ornamental Design for a Combined Ultra Violet Lamp and Shield, of which the following is a specification, reference being had to the accompanying drawing, forming a part thereof, in which

Fig. 1 is a perspective view of a combined ultra violet lamp and shield, showing my new design.

Fig. 2 is an elevational view of the device shown in Fig. 1.

Fig. 3 is a side view of the device shown in Figs. 1 and 2, with a portion of the reflector member cut away for illustrative purposes.

Fig. 4 is an end view of the same device.

I claim:

The ornamental design for a combined ultra-violet lamp and shield, as shown.

NORMAN A. WHITTAKER.
